SCRAPER FOR BANDS WITH A SENSITIVE SURFACE

Ernest Bleibler, Ghent, Belgium, assignor to Sylvania Industrial Corporation, Fredericksburg, Va., a corporation of Virginia

Application November 28, 1934, Serial No. 755,244
In Great Britain November 28, 1933

4 Claims. (Cl. 91—10)

This invention relates in general to an apparatus for treating with a liquid sheets or films in the form of endless bands or in continuous lengths, and in particular, to such an apparatus having a scraper adapted to remove surplus liquid from the surface of such sheets or films.

It is an object of this invention to arrange the scraper so as to remove in a substantially complete way the liquid which the band might 10 convey from one bath to the next.

It is a further object of this invention to vary and adjust within very wide limits the pressure, without there being any risk of the sheets or 15 films with the sensitive or delicate surface being crushed or creased or there being any fear that the band may be damaged in any other way, as by the formation of streaks, scratches or the like.

According to the invention there is provided an apparatus for treating sheets or films with 20 a liquid or liquids which comprises the combination of a treating vat containing a liquid, means to pass the sheet or film through the liquid in the vat, and a scraper positioned above the level of the liquid, the scraper comprising a pair of 25 rotatable, preferably cylindrical, wiping members, means to support the wiping members in spaced parallel relation and means adjustable for positioning these members in wiping contact with a sheet or film passing between the wiping 30 members. Where the sheet or film is especially fragile or has a delicate surface, the scraper may be further provided with means for resiliently holding the wiping members in contact with the surface of the sheet or film to avoid crushing or 35 damaging the surface in any way.

The bars may be made of any material chemically inert to the wet film or to the baths, suitable materials being glass, porcelain or metal, wood, stone or artificial masses such as resins 40 and the like.

The invention will be best understood on referring to the drawing affixed to my specification and forming part thereof which illustrates the invention as embodied in a preferred construction. It will be readily understood, however, 45 that my invention is by no means limited to this construction and that the scope of my invention and the ambit of my appended claims extends to any construction incorporating the broad 50 principle underlying my invention.

In the drawing:

Fig. 1 shows in transverse section the arrangement of the new scraper in the operative position on the band between two treatment baths.

Fig. 2 shows the scraper in the open position,

Fig. 3 is a front elevation of the scraper, while Figs. 4 and 5 are side elevations of arrangements for fixing the scraper in position in an adjustable and resilient manner.

Two successive baths are denoted by 11 and 12 through which a band 13 to be treated, principally one with a sensitive surface, is passed continuously. The scraper 20 is placed between the successive baths. It consists of two bars 21, 22 which run parallel with each other at a distance from each other and the endless band 13 is threaded between them. The bars are mounted to rotate, preferably freely, between suitable heads or flanges 25, 26 which are carried in their turn on shafts or spindles 35, 36 which 15 are rotatably mounted in suitable bearings 27, 28, as indicated diagrammatically in Fig. 3.

Fig. 2 shows the scraper in the open position in which the band is threaded through it. By rotating it in the direction indicated by the arrow, the scraper is brought into the operative position, in which the underside of the band bears against one scraper 21 and the top of the band against the other scraper 22. According to the pressure with which the bars are held 25 against the band, the pressure of the scraper can be regulated as may be desired. As this pressure can be altered to any degree of fineness by slightly altering the angle which the contact surface of the two spindles of the bars makes 30 with the surface of the band, it follows that the pressure of the scraper can be adjusted to any degree of fineness, so that allowance can be made for the particular conditions existing at the time, particularly the sensitiveness or other state of 35 the surface to be treated.

In the operative position (see Fig. 1) the bars are so adjusted and positioned with respect to the band that one bar 22 removes the liquid from the upper surface of the band 13 to be 40 treated so that it then runs back as shown at 30 over this surface into the bath 11. The scraper 21 removes the liquid from the underside of the band, the liquid falls downwards and passes at 45 31 on to a suitable drip pan 32, which returns it to the bath 11. In this way, most of the liquid carried up by the band 13 out of the bath 11 can be recovered without there being any risk of any appreciable quantity of liquid passing out of the bath 11 into the bath 12.

By constructing the scraper with two bars arranged at a distance from each other, the sensitive band is at the same time prevented from being squeezed as it might be if as is otherwise usual, the two scraper rolls arranged opposite 50

each other are pressed together and against the band lying between them.

In comparison with the known scraper rolls there is another advantage, namely that the cost of manufacture of the new scraper is considerably reduced, as the parts do not require to run exactly "round" as in the known scraper rolls, and therefore do not require such accurate adjustment, on the contrary it suffices to provide the bars with a smooth surface and drop them loosely into their bearings. At the same time the scraper according to this invention permits of the scraper rolls being conveniently cleaned while it is at work, should any matter out of the baths become deposited on the surfaces of the bars. In such case it will suffice to bring the scraper into the position shown in Fig. 2, and clean the bars off, which operation, in the case of glass bars, can be carried out with an acid.

The scraper can be fixed in the operative position by any desired means, say for example by providing one or both flanges, e. g. 26, on the outside with a series of openings 38 into which a bolt or a pin can be pushed. Means may also be provided in order to resiliently hold the bars in position, for example the spindle 36 being provided with an adjusting spring 37.

Since certain modifications in the apparatus which embodies the invention may be made without departing from its scope, it is intended that all matter contained in the above description or shown in the accompanying drawing shall be interpreted as illustrative and not in a limiting sense.

I claim as my invention:—

1. In an apparatus for treating sheets or films with a liquid, a scraper comprising a pair of rotatable cylindrical wiping members, means to support said members in spaced parallel relation, said supporting means adapted to be rotated to bring said members into wiping contact with a sheet or film passing therebetween, and means for resiliently holding said scraper in wiping position.

2. In an apparatus for treating sheets or films with a liquid, the combination of a plurality of treating vats containing liquids, means to pass a sheet or film successively through said vats in

contact with said liquids, a scraper positioned to contact the sheet or film as it passes from one vat to the next, said scraper comprising a pair of rotatable cylindrical wiping members, means to support said members in spaced parallel relation, said supporting means adapted to be rotated to bring said members into wiping contact with a sheet or film passing therebetween, and means adjustable for fixing said scraper in wiping position, and means positioned below the scraper for catching liquid scraped from said sheet or film and for returning said liquid to the vat from which the sheet or film has just issued. 5

10

3. In an apparatus for treating sheets or films with a liquid, a scraper comprising a pair of freely rotatable cylindrical wiping members, means to support said members in spaced parallel relation, said supporting means adapted to be rotated to bring said members into wiping contact with a sheet or film passing therebetween, and means for resiliently holding said scraper in wiping position. 15

20

4. In an apparatus for treating sheets or films with a liquid, the combination of a plurality of treating vats containing liquids, means to pass a sheet or film successively through said vats in contact with said liquids, a scraper positioned to contact the sheet or film as it passes from one vat to the next, said scraper comprising a pair of rotatable cylindrical wiping members, means to support said members in spaced parallel relation, said supporting means adapted to be rotated to bring said members into wiping contact with a sheet or film passing therebetween, and means adjustable for fixing said scraper in wiping position, and a plate positioned below said scraper and adjusted as to its form to the path of the sheet or film, said scraper in its wiping position and said plate being in co-operative relation for catching liquid scraped from the said sheet or film and for returning said liquid to the vat from which the sheet or film has just issued without any dripping of liquid to a surface of the film or sheet just cleaned, or without contaminating any following bath from liquid carried along by 40
